UNITED STATES PATENT OFFICE

164,616

COMBINED CLOCK AND DESK UNIT

Martin Weiner, Passaic County, N. J.

Application March 2, 1951, Serial No. 14,354

Term of patent 14 years

(Cl. D74—1)

To all whom it may concern:

Be it known that Martin Weiner, a citizen of the United States of America, now residing at State of New Jersey, county of Passaic, town of Clifton, has invented a new, original, and ornamental Design for a Combined Clock and Desk Unit, of which the following is a specification, reference being had to the accompanying drawing, forming a part thereof.

Fig. 1 is a plan view of a combined clock and desk unit, showing the essential features of my new design in full lines, the pen staff being shown in a broken condition in the remaining figures for convenience of illustration.

Fig. 2 is a front elevation; and
Fig. 3 is a side elevation.

I claim:

The ornamental design for a combined clock and desk unit, substantially as shown and described.

MARTIN WEINER.
